GAME BOARD

Gary G. Leggat, 12252 Memorial, Detroit,
Mich. 48227

Filed Jan. 11, 1968, Ser. No. 10,128

Term of patent 3½ years

U.S. Cl. D34—5
Int. Cl. D21—01

FIG. 1

FIG. 2

FIG. 3

FIG. 1 is a perspective view of the game board looking downwardly upon the game showing my new design.

FIG. 2 is an end elevational view thereof, both ends of the game presenting an identical aspect.

FIG. 3 is a side elevational view of the game, both sides of the game presenting an identical aspect.

The bottom of the device is plain and non-ornamental and no view thereof is shown.

I claim:

The ornamental design for a game board, as shown and described.
